[57] CLAIM

The ornamental design for a pocketed reusable cover letter, as shown and described.

DESCRIPTION

FIG. 1 is a front perspective view of a pocketed reusable cover letter showing my new design;

FIG. 2 is a front elevational view thereof;

FIG. 3 is a rear elevational view thereof;

FIG. 4 is a side elevational view thereof, the undisclosed side being the same;

FIG. 5 is a top plan view thereof, the undisclosed bottom being the same;

FIG. 6 is a front perspective view of a second embodiment of FIG. 1;

FIG. 7 is a front elevational view thereof;

FIG. 8 is a rear elevational view thereof;

FIG. 9 is a side elevational view thereof, the undisclosed side being the same;

FIG. 10 is a top plan view thereof, the undisclosed bottom being the same;

FIG. 11 is a cross-sectional view taken along line 11—11 of FIG. 3; and,

FIG. 12 is a cross-sectional view taken along line 12—12 of FIG. 8.
